(57) **CLAIM**

I claim the ornamental design for an electric outlet cover, as shown and described.

DESCRIPTION

FIG. 1 is a perspective view of an electric outlet cover, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged partial cross-sectional view thereof, taken along line 8-8 in FIG. 2; and,

FIG. 9 is an enlarged partial cross-sectional view thereof, taken along line 9-9 in FIG. 2.

The broken lines in the drawings show portions of the electric outlet cover that form no part of the claimed design.
